UNITED STATES PATENT OFFICE

2,204,388

PHOTOELECTRIC TUBE

Herbert Steyskal, Berlin, Germany, assignor to
General Electric Company, a corporation of
New York

Application January 28, 1938, Serial No. 187,521
In Germany March 3, 1937

3 Claims. (Cl. 250—166)

The present invention relates to photoelectric tubes and more particularly to light-sensitive tubes which depend on secondary electrons for their operation.

In the prior tubes of this general type, the anode is usually interposed between the primary and secondary cathodes, and is maintained at a potential more positive with respect to the primary cathode than the secondary emission cathode. Consequently, the photoelectrons emanated by the primary cathode when exposed to light necessarily move in the general direction of the anode on their way to the secondary cathode and in many cases, actually strike the anode. All of the electrons emitted by the primary cathode therefore do not reach the secondary cathode for the production of secondary electrons and a part of the amplification which the tube should have is lost.

An object of the present invention is to provide a phototube of the secondary emission type and having an electrode structure in which the primary electrons, in their travel toward the secondary emission electrode, do not strike the anode. Another object is to provide a tube of this character in which the secondary electrons, in their travel toward the anode, take a different path from the primary electrons in their movement toward the secondary emission electrode. A further object is to provide a phototube of the secondary emission type in which the anode is interposed between the primary and secondary cathodes, and the anode field is controlled in such a manner as to cause the anode to attract the secondary electrons but not the primary electrons. A still further object is to provide a phototube in which the photoelectrons emitted by the cathode are electrically and physically constrained from impinging on the anode, and only the secondary electrons emitted by the secondary emitting electrode are permitted to reach the anode. These objects are attained in brief by providing a shield member between the anode and the primary cathode, the shield being charged to such a potential as to direct the primary electrons away from the anode but still permit the secondary electrons emitted by the secondary cathode to reach the anode. The invention will be better understood in connection with the following description and the accompanying drawing in which Fig. 1 shows a sectional view of a phototube improved in accordance with the present invention and connected in an energizing circuit. Figs. 2 and 3 are perspective views of modified forms of the improved tube; Fig. 4 shows

a still further tube modification; Figs. 5 and 6 are fragmentary sectional views taken along lines 5—5, 6—6 respectively in Fig. 1. Figs. 7 and 8 are fragmentary sectional views taken along lines 7—7, 8—8 respectively of Fig. 4.

Referring to Fig. 1, numeral 1 designates an envelope of spherical configuration containing a pair of partially spherical electrodes 2, 3 of a conducting material, for example copper, mounted in position in any suitable manner. The interior surface of the electrode 2 is coated with light-sensitive material such as caesium oxide on silver, as is shown in Fig. 6, and applied in any suitable and well-known manner. This electrode when exposed to an external light source (not shown) serves the function of a primary cathode in providing photoelectrons. As shown in Fig. 5, the inner surface of the electrode 3 may be coated in any suitable and well-known manner with a material such as barium oxide on nickel which profusely emits secondary electrons when struck by primary electrons traveling at a high velocity. The anode of the tube is composed of a metallic body 4 of essentially punctiform character which is supported at a position central of the envelope.

When the secondary cathode 3 is maintained at a high potential with respect to the primary cathode 2 by means of a battery 5, and the anode is maintained at a still higher potential with respect to the cathode 2, photoelectrons produced at the inner surface of the electrode 2, when light impinges on this surface, are strongly attracted by the anode and the secondary cathode. The light may be directed through the opening 6 in the secondary cathode 3, or through the space between the electrodes 2, 3. Those electrons which reach the electrode 3 give rise to secondary electrons which are then attracted to the anode. Inasmuch as the number of secondary electrons generated at the electrode 3 may greatly preponderate over the number of primary reaching the electrode 3, amplification of the light-sensitive current is made possible. However, if, as in the prior art tubes, all of the photoelectrons generated at the electrode 2 do not reach the secondary emitter electrode 3 but instead, some of them go directly to the anode 4, the amplification obtained is not an optimum. This diversion of electrons is eliminated or at least substantially reduced in accordance with the present invention by providing a shield member or baffle 8 rigidly supported in the envelope in any suitable manner and positioned between the anode and the primary cathode. While the shield member may take any suitable shape, it is preferred to give it

a configuration similar to that of the primary cathode. The shield may be given any suitable potential, positive or negative with respect to the primary cathode and for this purpose, may be connected to the common source of potential 5. If desired, the shield member may be connected directly to the cathode 2. The electrical effect on the primary electrons introduced by the electrically charged shield member 8 is shown roughly by the dotted line *a* which indicates the path of a primary electron being diverted from the anode by the shield and moving toward the secondary cathode 3. As stated hereinbefore, for every electron which strikes the secondary cathode, more than one secondary electron may be generated, and the path of these electrons is indicated by the dotted line *b* which leads directly to the anode 4.

If the anode lead-in connection presents a conductive area comparable to that of the anode proper, it is in some cases advantageous to shield it also. This may be done either by covering it with a layer of insulating material or by providing an extended portion of the shield 8 adequate for the purpose stated.

Fig. 2 shows the application of the improved shields to an elongated cylindrical form of phototube provided with two or more centrally positioned anodes 10. Shields 11 of a hemispherical configuration may be provided about each anode, as in the case of the single anode tube of Fig. 1. If desired, the anodes may be connected together within the tube to form a loop, in which case a single shield may be employed having such a shape as to be interposed between all parts of the loop and the primary cathode. The primary cathode 12 may take the form of a light-sensitive coating of any suitable material such as caesium oxide on silver and applied directly to a limited portion of the envelope. The secondary cathode 13 may be of a size comparable to that of the light-sensitive coating 12 but positioned diametrically opposite from the latter. A foundation layer of metal 45 may be applied directly to the glass, and secondary emission material such as barium oxide coated on the foundation layer. This secondary emitter member preferably has an aperture 14 through which light may enter the tube and impinge on the light-sensitive cathode 12. The light might also be directed through the space between the coatings or even through the secondary cathode if it is sufficiently transparent. As in the case of Fig. 1, the shields 11, when 55 charged to the proper potential with respect to the primary and secondary cathodes, serve to redirect the photoelectrons away from the anodes and to cause them to strike the secondary emitter electrode. A circuit arrangement similar to that shown in Fig. 1 may be employed to provide the necessary electrostatic fields.

The tube shown in Fig. 3 is of the same general type as that illustrated in Fig. 1 except that the primary and secondary cathodes are applied directly to the envelope rather than being constituted of a coating on metal members mounted apart from the envelope. The light-sensitive coating 15 may be constituted of caesium oxide or any other light-sensitive material, and the secondary emitter coating 16 may be composed of barium oxide or any other suitable secondary emission material. Leads are taken from these coatings to the exterior of the envelope through the reentrant stem 17. The anode may comprise 75 a rigid rod 18 which terminates at the central

position of the bulb. The shield 19 may constitute a hemispherical member, as in the case of Figs. 1 and 2, and connections from this member and all of the electrodes taken to a source of current such as a battery (not shown).

Fig. 4 represents a tube somewhat similar to that shown in Fig. 3 in that the primary and secondary cathodes 15, 16 are constituted of coatings applied directly to the envelope but in this case, the anode and the electron shield or baffle are constituted of the well-known heater and sputter shield members which would normally be provided in tubes of this sort. In those tubes having a coating applied directly to the envelope, it is customary, as shown in the 15 Ruggles Patent No. 1,568,694, to provide a heater for vaporizing the foundation metal and also to provide a sputter shield for preventing the deposition of the metal on undesired portions of the envelope. In case two separate coatings are 20 employed, as shown in this figure, two heaters and two shields would normally be provided for the purposes mentioned. After the coatings have been applied, the heater and sputter shields could conveniently be used for the regular anode, 25 also as an improved shield for intercepting or diverting the primary electrons away from the anode in accordance with the present invention. However, it would be noted that only the heater designated by the reference character 20 which is 30 further removed from the cathode 15 is in the proper position to be shielded from primary electrons by the immediately adjacent shield 19 and hence, only this heater can be employed as the anode. As in the case of the previous 35 figures, the primary and secondary cathodes 15, 16, also the anode 20 and the shield 19, may be connected to a common source of current which provides the necessary fields within the tube to cause the secondary electron emission and 40 shielding effects.

What I claim as new and desire to secure by Letters Patent of the United States is:

1. A discharge device including a primary cathode of relatively extensive surface area, a 45 secondary emission electrode positioned in spaced relation to the primary cathode to receive electrons therefrom, an anode interposed between the primary cathode and the secondary emission electrode and effective during operation of the 50 device to receive current from the secondary emission electrode, said anode being essentially punctiform so as to offer little physical obstruction to the passage of current from the primary cathode to the secondary electrode, and a baffle 55 interposed between the anode and the primary cathode for shielding the anode from electrons emitted by the cathode.

2. A discharge device including a primary cathode in the form of a partial surface of revolution, a secondary emission electrode also in the form of a partial surface of revolution and positioned in opposite relation to the primary cathode to receive electrons therefrom, an anode interposed between the primary cathode and the 65 secondary emission electrode and effective during operation of the device to receive current from the secondary emission electrode, said anode being essentially punctiform and being positioned approximately at the common center 70 of revolution of said cathode, and secondary emission electrode, and a baffle interposed between the anode and the primary cathode, said baffle intercepting substantially all straight lines 75 between the anode and the cathode, thereby to 75

minimize collection by the anode of electrons emitted from the cathode.

3. A photoelectric tube comprising an envelope containing a light sensitive electron-emitting cathode of concave hemispherical form, a secondary emission electrode having a configuration similar to that of the cathode and positioned in opposed relation thereto, an anode interposed between the said cathode and secondary emission electrode and effective during operation of the device to receive electrons from the latter,

said anode being essentially punctiform and being positioned approximately at the common center of curvature of the cathode and the secondary emission electrode, and a baffle interposed between the anode and the light sensitive cathode for deflecting electrons emitted from the cathode and proceeding toward the secondary emission electrode, said baffle being of materially smaller area than the cathode.
